CONVERTIBLE STATION WAGON

Clifford Brooks Stevens, 8041 N. Graylog Lane,
Milwaukee, Wis.

Filed Mar. 14, 1960, Ser. No. 59,733

Term of patent 14 years

(Cl. D14—3)

The broken lines represent portions of the automobile visible through the windshield and side windows.

I claim:

The ornamental design for a convertible station wagon, as shown and described.
